UNITED STATES PATENT OFFICE.

ERNEST N. JOHNSON, OF WINNIPEG, MANITOBA, CANADA.

SWITCH RAIL.

Application filed May 1, 1923. Serial No. 635,927.

To all whom it may concern:

Be it known that I, ERNEST N. JOHNSON, a subject of the King of Great Britain; of the city of Winnipeg, in the Province of

5 Manitoba, Canada, have invented certain new and useful Improvements in Switch Rails, of which the following is the specification.

The invention relates to improvements in switch rails for railroad purposes and the 10 general object of the invention is to provide a simply constructed, easily operated, positive and easily installed switch rail which can be manipulated to connect intersecting tracks as occasion may demand.

15 A more particular object of the invention is to improve the construction of the switch rail previously invented by me and as fully set forth and described in my United States Patent No. 1,393,538 dated October 11th, 20 1921, the improvements relating more particularly to the general arrangement of the base plate, top plate and other plates and fittings associated therewith, whereby the same can be more easily manufactured and 25 assembled and also to the locking bar and parts associated therewith, whereby the same is at all times absolutely positive in its action and also whereby the same can be readily repaired when required.

30 With the above more important objects in view the invention consists essentially in the arrangement and construction of parts hereinafter more particularly described and later pointed out in the appended claims, reference being had to the accompanying drawings in which:—

Fig. 1 is a plan view of the invention showing it in the position where it connects the main line rails.

40 Fig. 2 is a side view of the parts appearing in Figure 1.

Fig. 3 is an enlarged view similar to Fig. 1 with the switch rail, clips and dust plates removed.

45 Fig. 4 is a view similar to Fig. 3 with the parts in the position in which the turn out rail is connected, to the side rail and prior to the same being locked in such position.

Fig. 5 is an enlarged detailed vertical sectional view at 5—5' Fig. 1.

50 Fig. 6 is a vertical sectional view at 6—6' Figure 3.

Fig. 7 is a plan view of the base plate and certain other parts associated therewith.

Fig. 8 is an enlarged plan view of the 55 swivel plate and other parts showing more particularly the detailed features of the slot 24.

In the drawings like characters of reference indicate corresponding parts in the 60 several figures.

In the present disclosure I have only considered it necessary to show the device as it appears associated with the adjoining portions 1 and 2 of the main line rail and the 65 adjoining portions 3 and 4 of the turn out and side rails. These portions of the main line, turn out and side rails lead to the device in the ordinary way and are securely bolted together as indicated at 5 and 6, suitable spacing blocks 7 and 8 being utilized as is customary. The rails ride the ties or sleepers 9. A base plate 10 is provided, this base plate resting on the ties and having the 70 ends thereof extended to underlie the connected ends of the rails hereinbefore mentioned.

75 On the ends of the base plate I locate end plates 11 and 12 which are permanently riveted or otherwise fastened to the meeting 80 ends of the rails 1, 3,—2, 4, and these end plates are securely fastened by bolts 13 and 14 to the base plate.

85 Between the end plates and on the base plate I mount a swivel plate 15, the said swivel plate having one end pivotally held to the base plate by a king bolt or pivot pin 16. The ends of the swivel plate are cut concentric to the bolt 16 as are also the inner 90 ends of the end plates 11 and 12, which latter slidably engage the ends of the swivel plate.

95 On the swivel plate I mount a lengthwise extending switch rail 17 which is fastened thereto by suitably placed clips 18. The switch rail, in the turning movement of the swivel plate, is adapted to connect the through portions 1 and 2 of the main line rail or the turn out rail 3 to the side rail 4, depending on the setting thereof. The switch plate is held down by pairs of clip 100 plates 19 and 20 bolted to the end plates and having their inner ends overlying the ends of the swivel plate.

105 Means, shortly described, are provided for shifting the swivel plate and locking the same in shifted position, such being operated from a suitable tower or other station. The base plate is provided with two trans-

versely extending suitably spaced slots 21 and 22 and to the underside of the swivel plate I permanently rivet a stop plate 23 which is received within the slot 22 and, by contact with the ends of the slot, is adapted to positively limit the swinging movement of the swivel plate, the limiting positions of the swivel plate being when the switch rail is aligned with the rails 1 and 2 or with those 3 and 4. The swinging or free end of the swivel plate 15 is provided with a slot 24 which is provided with an offset portion 25, the offset portion forming two right angled shoulders or stops 26 and 27. The slot 24 is above the slot 21 and the said slots receive a shiftable locking bar 28 which has the lower part thereof contracted and mounted for operating in the slot 21 and the upper part thereof somewhat larger and mounted for operation within the slot 24 and offset 25. The locking bar has the ends thereof somewhat larger than the body part and the ends are preferably case hardened steel. The locking bar is adapted, when shifted endwise, to actuate the swivel plate 15, turning it from one limiting position to the other and when so turned to lock the swivel plate against movement.

In Figure 3 I have shown the locking bar in full outline in the position which it has when the switch rail is connecting the main line rails 1 and 2 and is being locked in such position by the locking bar. In said figure I have shown in dotted outline the position which the shifted locking bar has when the swivel plate is released and when it is about to move with the locking bar.

In Figure 4 I have shown the swivel plate in the position where the turn out rail 3 and the side rail 4 are connected by the switch rail and the locking bar in full outline in the position occupied after it has fully shifted the swivel plate and prior to locking the same. In dotted outline in said latter figure I have shown the locking bar in the position which it has when it locks the swivel plate.

By observing these figures it will be apparent that in the limiting positions of the swivel plate and of the locking bar, the swivel plate cannot move unless the locking bar be shifted. When the locking bar is shifted in either direction from extreme positions the inner end of the locking bar strikes the shoulder (26 or 27) and in striking the shoulder positively causes the swivel plate to move with it, the movement of the plate continuing until the switch rail has been brought to its proper position in respect to the other rails, at which time the advancing end of the locking bar is adapted to clear off the shoulder and enter the end of the slot 24.

In my prior patent herein before mentioned the locking bar did not engage with

abrupt or right angled shoulders and I have found, by experience, that in such prior construction the action was not at all times positive.

The present arrangement provides a construction which can at all times be relied upon and which is much more simple to manufacture and easier to assemble.

The locking bar and parts immediately associated therewith are enclosed beneath dust plates 29 and 30 bolted to the swivel plate. The locking bar is provided with a centrally disposed pin 31 which projects downwardly beneath the base plate and is connected to a shifting bar 32 which can be operated in any suitable manner to effect the proper movement of the locking bar at the required times. The pin 31 has the head thereof countersunk in the top face of the locking bar and is retained in place by the dust plates and base of the switch rail.

I wish now to refer particularly to Figure 8, wherein the details of the slot 24 are better shown. In the construction of this slot it is necessary that the faces 33 and 34 adjoining the shoulders be in a fixed position relative to one another and this position is such that, if the said faces be projected to intersect, the angle indicated at "a" and formed at the intersection, will be equal to what is known as the frog angle. This angle is actually the angle "b" between the rails 2 and 4 or, which is the same thing, the angle between the rails 1 and 3.

The offset 25 is simply of such a nature that clearance is given the locking bar 28 when it is moving in either direction from central position.

In connection with the slots 24 and 21, it is necessary that the faces 33 and 34 lie flush with the inner edge of the slot 21 at the time the advancing end of the locking bar 28 is escaping from the shoulders 26 and 27.

When the locking bar is in its extreme positions it positively locks the swivel plate against movement owing to the fact that in such positions it cannot move in a circular path concentric to the swivel pin 16 and consequently should the swivel plate attempt to move it will be bound by the locking bar, the movement of which is constrained by the straight slot 21. The value of the offset is obviously to give sufficient clearance to allow the locking bar to shift in the slots without binding when the same is moved.

In order to give a clear understanding of the present invention as compared with that disclosed in my prior patent I now point out the following:

In my prior construction the locking bar had a fixed but changing path of travel in respect to the base plate which introduced structural complications which necessitated considerable manufacturing costs and permitted considerable possibilities of wear.

In the present application the locking bar has a fixed and straight path of travel in respect to the base plate which permits of simplified construction and decreased cost of production and also allows of the easier manipulation of the locking bar by virtue of the straight path of travel.

In the prior patent the locking bar actuated the swivel plate by frictional contact, whilst in the present case the action is a direct and positive thrust between the parts for the entire movement, such being brought about by contact of the locking bar with either of the shoulders. Further, in the prior disclosure the parts had to be designed and adjusted to such a nicety to work satisfactorily that the device could not be relied upon when installed under ordinary conditions as met with in railroad track work. The present device has been designed so that it can be installed and relied upon with only a reasonable amount of care being exercised when installing.

What I claim as my invention is:

1. The combination with a main line, a turn out and a side rail, of a base plate permanently secured to and supporting the aforesaid rails, said base plate having a transverse slot therein, a top plate pivotally secured to the base plate and movable laterally between predetermined fixed limiting positions, said top plate having a slot therein and with the latter slot having one side presenting converging working faces with a clearance space reserved between the said working faces, a switch rail permanently mounted on the top plate and adapted in the limiting positions of the top plate to connect the main line rails or the side rail and turn out rail and a shiftable locking bar operating within the slots and having a straight path of travel in the slot of the base plate and adapted to engage with the working faces of the top slot in the end shifting of the locking bar.
2. The combination with a main line, a turn out and a side rail, of a base plate permanently secured to and supporting the aforesaid rails, said base plate having a transverse slot therein, a pivoted top plate having a slot therein and movable laterally between predetermined fixed limiting positions, said latter slot presenting converging working faces having their inner ends terminating in abrupt shoulders, there being a clearance space reserved between the shoulders, a switch rail permanently secured to the top plate and adapted to connect, in the limiting shifted positions thereof, the main line rails or the side rail and turn out rail, and an endwise shiftable locking bar operating in the slots and adapted to engage with the shoulders and when so engaged shift the top plate in one direction or the other, depending on the direction of travel, and move the same to its limiting position and adapted further and subsequently to clear the shoulder and pass into the ends of the slots and positively lock the top plate against movement.
3. The combination with a main line, a turn out and a side rail, of a base plate permanently secured to and supporting the aforesaid rails, said base plate having a transverse slot therein, a top plate having one end pivotally secured to the base plate and the other end laterally movable between predetermined limiting positions and provided in the latter end with a slot, one side of the slot presenting converging working faces, said working faces having their inner ends terminating in abrupt shoulders separated by a clearance space, a switch rail permanently secured to the top plate and adapted in one of the limiting positions thereof to connect the main line rails and in the other limiting position to connect the side rail and the turn out rail and an endwise shiftable locking bar operating within the slots and having a straight path of travel in the slot of the base plate and adapted to engage with one or other of the shoulders in the end shifting thereof and in so doing shift the top plate to its limiting position in that direction and subsequently to escape from the shoulder into the ends of the slots and lock the top plate against movement.
4. In combination, a fixed base plate having a transverse slot therein, a top plate having one end pivotally connected to the base plate and the other end laterally swingable over the base plate and provided in said latter end with a slot, the said slot having one side presenting converging working faces having their inner ends terminating in abrupt shoulders and with the shoulders separated by a clearance space and a locking bar entering both slots and endwise shiftable therein and having a straight path of travel in the slot of the base plate and adapted when end shifted to engage one or other of the shoulders and move the top plate a predetermined distance and subsequently clear from the shoulder and pass into the end of the slot and lock the top plate against movement in the shifted position.
5. The combination with a main line, a turn out and a side rail, said main line and side rail intersecting at a predetermined angle termed the frog angle, of a base plate permanently secured to and supporting the aforesaid rails and provided with a transversely extending slot, a top plate having one end pivotally attached to the base plate and the other end provided with a slot, said latter slot having one edge thereof presenting converging working faces intersecting at the frog angle and separated by a clearance space and an endwise shiftable locking bar operating within the slots and having a

straight path of travel in the slot of the base plate and adapted when shifted in either direction to shift the top plate a predetermined distance by contact with the aforesaid 5 side of the slot in the top plate and subsequently to pass into the end of the said slot and lock the top plate against further movement.

6. The combination with a main line, a 10 turn out and a side rail, said main line and side rail intersecting at a predetermined angle termed the frog angle, of a base plate secured to and supporting the aforesaid rails, said base plate having a transverse slot 15 therein, a top plate having one end pivotally attached to the base plate and the other end laterally shiftable and provided with a slot, the said latter slot having one side presenting converging faces intersecting 20 at the frog angle and with the said converging faces having their inner ends terminating in abrupt shoulders separated by a clearance space, means positively limiting the lateral shifting movement of the top 25 plate, a switch rail permanently secured to the top plate and adapted in one of the limiting positions thereof to make a through main line rail connection and in the other of its limiting positions to connect the side rail 30 with the turn out rail and an endwise shiftable locking bar operating within the slots and having a straight path of travel in the slot of the base plate and adapted when shifted in either direction to engage with one 35 or other of the shoulders and shift the top plate to its limiting position and, having shifted the top plate to such position, to escape from the shoulder and enter the end of

the slot and in so doing lock the top plate 40 against shifting.

7. The combination with main line, turn out and side rails, of a base plate underlying the ends of the rails, end plates permanently secured to the ends of the rails and bolted to the base plate, a top plate mounted on the base plate and positioned between the end plates, said top plate having one end pivotally attached to the base plate, the said rails, end plates and top plate having their adjacent ends cut concentric to the pivot point 50 of the top plate, pairs of clip plates permanently secured to the end plates and having their inner ends overlying the ends of the top plate, a switch rail permanently secured to the top plate and adapted in the 55 shifting of the top plate in one direction to make a through main line rail connection and in the shifting of the top plate in the other direction to connect the side rail with the turn out rail and a stop plate 60 permanently secured to the underside of the top plate and operating within a slot provided in the base plate and adapted to engage with the ends of the slot in the shifting of the top plate and stop the movement thereof 65 when the said switch rail is forming a through main line rail connection or when the said switch rail is connecting the side rail with the turn out rail.

Signed at the city of Winnipeg, in the 70 Province of Manitoba, this 20th day of March 1923.

ERNEST N. JOHNSON.

In the presence of—
GERALD S. ROXBURGH,
M. B. KELLEHER.
